R. M. KEMPF,
SHOE LACE HANGER.

APPLICATION FILED NOV. 26, 1919.

1,347,277.

Patented July 20, 1920.

UNITED STATES PATENT OFFICE.

ROMAN M. KEMPF, OF COLUMBUS, OHIO.

SHOE-LACE HANGER.

1,347,277.

Specification of Letters Patent. Patented July 20, 1920.

Application filed November 26, 1919. Serial No. 340,872.

To all whom it may concern:

Be it known that I, ROMAN M. KEMPF, a citizen of the United States, residing at Columbus, in the county of Franklin and State 5 of Ohio, have invented certain new and useful Improvements in Shoe-Lace Hangers, of which the following is a specification.

This invention relates to an improved hanger for effecting the support of shoe 10 laces, and embodies means whereby a relatively large number of such laces may be securely retained within the hanger against accidental displacement, and to provide resilient means in connection with said 15 hanger for placing pressure upon said laces so that said pressure will be constantly exercised upon the laces remaining in the hanger even after a large number thereof have been withdrawn.

20 The invention accordingly consists in a lace holding and dispensing hanger which may be efficaciously employed in shoe factories or other similar establishments wherein large quantities of such laces are being 25 handled, the invention providing means whereby such laces may be maintained in an orderly and conveniently arranged manner to that the same will be readily available for utilization and wherein but a minimum of 30 time will be lost in effecting a proper selection of shoe laces for varying needs.

The invention further consists in the provision of a shoe lace hanger embodying an open sided casing in which is resiliently 35 mounted a pressure plate, springs being mounted between said plate and the upper portion of said casing, whereby said plate will be normally forced in a downward direction to apply pressure upon shoe laces, or 40 other similar devices, confined between the plate and the bottom of the casing, said plate being automatically forced in a downward direction upon the withdrawal of laces from 45 the casing by responding to the action of said springs so that the shoe laces remaining in said casing, regardless of their number, will be firmly retained against accidental 50 displacement so that their accessibility and orderly arrangement will be continuously effected.

A further object of the invention resides in providing means for effecting the support of said casing, and to connect said means with said pressure plate, in order that said 55 means may be utilized in withdrawing the pressure plate and its coöperating spring

structure from the casing for the purpose of refilling the latter.

A still further object resides in securely retaining the pressure plate in its operative 60 position within said casing and to prevent undue slippage of the same from such operative position, said means operating, however, to permit of free vertical movement on the part of said pressure plate. 65

The invention further consists in the novel features of construction, combinations of elements, and arrangement of parts, herein-after to be fully described and pointed out in the appended claims. 70

In the accompanying drawing, forming a part of this specification, and in which similar characters of reference denote like and corresponding parts throughout the several views thereof; 75

Figure 1 is a side elevation of the improved lace holding bracket comprising the preferred form of the present invention, the pressure plate being shown in spaced relation from the bottom of the casing so as to 80 be in a position to permit of the insertion of laces into the bracket.

Fig. 2 is a horizontal sectional view taken along the line 2—2 of Fig. 1, and

Fig. 3 is a transverse vertical sectional 85 view the plane of which being disclosed by the line 3—3 of Fig. 1, showing a plurality of strings or laces in applied position within the hanger.

Referring more particularly to the structural details of the invention, use is made of a shoe lace supporting hanger which is designated in its entirety by the numeral 1. This hanger preferably consists of an open sided casing B, which is formed ordinarily 90 from thin sheet metal and is constructed to embody parallel end walls 2 and connecting top and bottom walls 3 and 4 respectively. The marginal portions of the walls 2 and 4 are curved, as indicated at 5, so that sharp 95 edges in the hanger will be eliminated, in order to reduce the liability of injury to the laces contained within said hanger. 100

Slidably mounted for vertical movement within the casing is a pressure plate 6, which 105 is located in parallelism with the top and bottom walls of the casing. The ends of the rear edge of the plate are provided with offset tongues 7, which coöperate with the vertical rear edges of the end walls to guide said 110 plate in its vertical movement, and also to prevent said plate from being horizontally

displaced by forwardly directed pressures. Spaced from the plate 6 and normally disposed in engagement with the under side of the top wall 3 is a horizontally extending bearing plate 8, said latter plate being normally disposed between the downwardly turned flanged edges 9 of said top wall. Obviously, through the medium of the edges 9, undue horizontal movement on the part of the bearing plate will be precluded. The plates 6 and 8 are provided with stamped out eye portions 10 which are adapted to receive the extremities of a pair of coiled springs 11, which latter serve to normally force said plates into engagement with the top and bottom walls of the casing. The plate 8 carries a fixed supporting hook 12, whose lower end is soldered or otherwise rigidly secured and connected in any substantial manner to said plate and by means of which the hanger as a whole may be suspended from a fixed point. Also, the shank of the hook 12 extends through a lateral slot 13 formed in the top wall 3 in order to permit of the removal of the resilient pressure applying structure. To accomplish such removal, the hook is forced downwardly against the tension of the springs 11. This lowers the bearing plate 8 to a position independent of the flanged edges 9. Then, by sliding the hook laterally both of said plates may be conveniently freed from their operative positions within said casing.

In operation, a suitable quantity of shoe laces, such for example as shown in Fig. 3, are positioned within the hanger between the bottom wall 4 thereof and the pressure plate 6. These laces are so positioned that their longer extremity 14 will hang downwardly from the forward side of the casing, and the shorter extremities 15 of said laces will depend from the rear side of the casing. When in this position the springs 11 will be under tension, so that sufficient pressure will be exercised upon said laces to securely retain the same in the manner described. To remove one or more of the laces, the longer extremity 14 of one of the same is grasped and pulled downwardly so as to effect the extraction of the lace against the pressure exercised thereon by the plate 6. It will be understood that by pulling the laces forwardly, the location of the plates 6 and 8 will be maintained, owing to the fact that

the tongue 7 of the plate 6 serves to prevent forward movement of the pressure plate, and also this feature is enhanced by the engagement of the shank of a hook with the inner end of the slot 13. From this construction it follows that even after a relatively large number of the laces have been removed from the hanger the tension on the remaining laces will still be constant and accidental displacement thereof prevented. As is set forth, the hook 12 serves in a dual capacity, first in supporting the hanger as a whole, and secondly in providing convenient means for removing the resilient pressure applying structure. Also, the parts of the hanger are so correlated that the operative positions of said plates will be maintained against the lateral pressure set up by the removal of the laces. The construction described is particularly useful in retaining such laces in an orderly and well arranged manner and in shoe factories it is particularly useful for those engaged in the task of lacing shoes.

I claim:

1. A hanger for holding shoe laces comprising an open sided casing, a clamping plate slidably mounted between the end walls of said casing, a bearing plate arranged in the top of said casing, spring means situated between said bearing and clamping plates and serving to force the bearing plate into engagement with the top of the casing and the clamping plate toward the bottom of the casing, and a hanger supporting member connected with said bearing plate.

2. A bracket for holding shoe laces comprising a rectangular casing, a horizontally situated clamping plate slidably mounted within said casing between the end walls thereof, a bearing plate removably mounted in the top of said casing, coil springs situated between said bearing plate and said clamping plate and normally serving to force the latter toward the bottom of said casing, and a hook member rigidly carried by said bearing plate and adapted to occupy a slot formed in the top of said casing, said hook member permitting of the withdrawal of said plates from said casing.

In testimony whereof I affix my signature.

ROMAN M. KEMPF.
